UNITED STATES PATENT OFFICE.

JAMES A. LANSING, OF SCRANTON, PENNSYLVANIA.

RANGE.

1,319,778.

Specification of Letters Patent.

Patented Oct. 28, 1919.

Application filed December 16, 1916. Serial No. 137,340.

To all whom it may concern:

Be it known that I, JAMES A. LANSING, a citizen of the United States, residing at Scranton, in the county of Lackawanna and 5 State of Pennsylvania, have invented certain new and useful Improvements in Ranges; and I do hereby declare the following to be a full, clear, and exact description of the same, reference being had to the accompanying drawings, forming part of this 10 specification.

This invention relates to improvements in domestic ranges, particularly of the type disclosed in my prior Patents, No. 1,021,640, 15 dated December 22, 1914, and No. 1,153,322, dated September 14, 1915. In the type of range therein disclosed, the ordinary open gaseous fuel burners and oven are supplemented by a firebox adapted for the consumption of solid fuel, and on one side of the firebox is a second combustion chamber in which gaseous fuel burners are arranged. Provision is made in the construction disclosed in both of said patents for the heating 20 of water either by the consumption of solid fuel in the firebox, or gaseous fuel in the gaseous fuel combustion chamber, or both. The earlier Patent No. 1,021,640 attains this end by means of a water front or chamber 25 for the circulation of water, which is interposed between the firebox and the gaseous fuel combustion chamber so that heat generated in either chamber will impinge on the side of the water front and heat the 30 water circulating therein. In the later Patent No. 1,153,322, the same result is attained by a different means; that is, instead of the water front, water-circulating coils are employed which extend into both the 35 gaseous fuel combustion chamber and the firebox.

The object of the present invention is to provide a construction wherein all the advantages of both types of water heating 45 media, set forth in the patents above enumerated, are retained and, as a consequence, a construction of maximum heating efficiency is produced. Briefly stated, the present construction contemplates the use 50 of a water front interposed between the solid fuel firebox and the gaseous fuel combustion chamber, and the use of coils located over the burners in the gaseous fuel combustion chamber, with provision for 55 maintaining circulation of water in the coils independent of the circulation in the

water front. In this manner, all the advantages of causing heated products of combustion, either in the firebox or the gaseous fuel combustion chamber, to impinge 60 against the side of a water front are retained, coupled with the distinct advantage derived from the use of coils located directly above the burners in the gaseous fuel combustion chamber. A much greater 65 heating efficiency is the result, when gaseous fuel is employed, without in any way detracting from the heating efficiency, when burning solid fuel.

With the above end in view, the invention 70 consists in the improved construction, arrangement and combinations of parts, pointed out in the claims at the end of the specification. A full understanding of the invention will be attained from the ensuing 75 detailed description, when taken in connection with the accompanying drawings, which illustrate a structural embodiment of the invention in a preferred form.

In the drawings:—

Figure 1 is a longitudinal vertical sectional elevation of a range provided with the present improvements.

Fig. 2 is a fragmentary horizontal section looking downwardly on the combustion chamber and the firebox.

Fig. 3 is a fragmentary horizontal section on the line 3—3 of Fig. 1.

Fig. 4 is a perspective view with portions of the stove broken away showing one arrangement of coils in the gaseous fuel combustion chamber.

Fig. 5 is a view similar to Fig. 4 but showing a modified arrangement of coils.

Fig. 6 is a view, also similar to Fig. 4, but showing a further modified arrangement of coils.

Like letters of reference in the several figures indicate the same parts.

The general range construction may be 100 of any preferred type and, in the present embodiment, the range is provided with an oven A adapted to be heated by a gaseous fuel burner or burners A'. In the space B above the oven are the usual open burners 105 B' B², assembled, in a manner well understood in the art, beneath a stove top plate C of the ordinary construction having burner openings c.

The products of combustion from the oven 110 burner A' flow into channels a, a' located respectively between the oven A and the

outer and inner transverse walls A² and G. The inner wall G separates the oven from the solid fuel firebox, a description of which will hereinafter appear. From the channels 5 *a*, the products of combustion pass through an opening D', at the back of the range into the flue box D. In the flue box D is a suitable plate damper D² mounted on an operating rod D³ which extends transversely across 10 the range and through the front panel, whereby the damper may be shifted from the front of the range to regulate the flow from the channels *a* into the flue box D. To insure a slight draft even when closed, the 15 damper plate D² is preferably perforated. Such a construction is particularly useful in gas ranges, since it insures the noxious gases passing off under all conditions. The flue box is located at the back of the range and 20 is connected with a flue E through which the products of combustion and gases in the flue box may pass into the atmosphere.

Located at one side of the oven is a firebox F adapted for the consumption of solid fuel. 25 This box may be of the usual type and has its side nearest the oven and its front and rear ends lined with fire bricks F'. The fuel is supported by grate bars F² located in the lower portion of the firebox. The transverse 30 wall or partition G separates the firebox from the oven A and the open burners B, and said partition is preferably provided with an angularly-disposed deflecting plate G' located beneath the grate bars F² for 35 directing the ashes and clinkers from the grate into an ashpit H beneath the firebox.

On the side of the firebox opposite from the oven A is a combustion chamber K for the burning of gaseous fuel. This gaseous 40 fuel combustion chamber is entirely independent of the firebox and its ashpit so that dust will not find its way into the same, and is inclosed on its outer side by the removable end wall M' of the range, and on its inner 45 side by the water front or chamber L, which is fitted in the transverse partition L'. With this construction, the water front itself forms the medium separating the gaseous fuel combustion chamber from the solid fuel 50 firebox, and, as a consequence, one face of the water front is exposed to the gaseous fuel combustion chamber and the other face thereof is exposed to the solid fuel firebox. The removable end wall M' is preferably the 55 inner wall of a door M having slide-damper controlled openings *m* therein at top and bottom through which air is admitted to the lower part of the gaseous fuel combustion chamber a considerable distance below the 60 water back. The door M fits an opening in the permanent end wall M² of the range structure.

The gaseous fuel combustion chamber K communicates with the flue box D at the rear 65 of the stove through an opening N, and a

plate damper O mounted in the flue box is adapted to control the flow from chamber K into the flue box. As shown, said damper O is pivotally mounted at its lower edge in the box so as to turn up into position for 70 preventing access to the box through the opening N, or down into position for permitting free passage of the products of combustion therethrough. A long damper O' is preferably combined with the flue box 75 damper O, the long damper O' controlling a correspondingly shaped opening l in the wall L' between the gaseous fuel combustion chamber K and the firebox F. As shown, the arrangement is such that when damper 80 O is opened, damper O' is closed and vice versa. For this purpose damper O' is mounted on the rod o on which the damper O is also mounted, but damper O' is disposed at a different angle from damper O. 85 Rod o extends out beyond the front of the range where it is readily accessible, and by oscillating the rod toward the left damper O is shut and damper O' opened. Reverse movement of the rod will open damper O 90 and concurrently close damper O'. When the long damper O' is opened, the heated products of combustion from the gaseous fuel chamber K are permitted to pass through the upper portion of the firebox F 95 to the flue box D and stack connection E. This arrangement is desirable inasmuch as it permits of the utilization of such heated products for the purpose of drying out or incinerating garbage, etc., which may be placed 100 over the firebox in a suitable receptacle without the necessity of building a fire in the firebox. Or the heated products may be utilized in this manner to augment heating of water in the water front L, as will herein- 105 after appear.

According to the present invention, the heat generated in the gaseous fuel combustion chamber is adapted to be transferred to water flowing in a coil or series of coils 110 in said chamber and also to sweep up against the water front L between the said chamber and the firebox, so that the water both in the coil and water front is simultaneously subjected to the heating action, although circulation in said water front is maintained independently of the circulation in the coil. Thus, two independent heat-circulating media are simultaneously subjected to the heating action of the gaseous fuel and it follows that a much larger quantity of water may be heated to an equal temperature without increasing the consumption of fuel, than would be the case if the coil or the water front alone were employed. In the form of the invention illustrated in Figs. 1 to 4, inclusive, a pair of long gas burners R, R' are arranged one above the other in the combustion chamber K. Each burner is double-barreled, *i. e.*, 130

consists of two long supply pipes respectively provided with outlet holes r' , and the several burners are preferably independently controlled, thus making it possible to regulate the fuel consumed in the chamber K within a wide range. For example, both burners may be lighted to first heat the water quickly and then one may be extinguished, and the heat maintained with the consumption of a comparatively small volume of gas.

The pipe P leading from the lower end of a suitable boiler (not herein illustrated but of any construction preferred by those skilled in the art) is connected with a coupling P' having two branches p , p' . One branch of said coupling is connected with the inner end of a coil Q consisting of a pair of pipes horizontally disposed with relation to each other and extending directly above the lower burner R. At their front ends the pipes are connected by an elbow q . At its rear end, one of the pipes of the coil Q is connected by a vertical elbow q' with a pipe of a second coil Q' arranged above the upper burner R'. The second coil Q' is in all respects similar to the coil Q and one of its pipes is connected at q'' with a branch s of a coupling S in which is secured the outlet pipe S'. The branch p' of coupling P' is joined with a pipe T forming the inlet for the water front L and similarly branch s' of coupling S is joined with a pipe T' forming the outlet for said water front. Outlet pipe S' leads to the upper end of a boiler in the usual manner. With the above arrangement, it will be noted that while common inlets and outlets are provided for the coils Q, Q' and the water front L, yet water may be circulated in the coils independently of the water front and vice versa.

If it be desired to heat the water by the consumption of gaseous fuel in the chamber K the burners R, R' are lighted, and the heat from said burners is transferred to the coils Q, Q' located directly over the burners, and is also caused to impinge against the side of the water front facing the gaseous fuel combustion chamber. The water both in the coils and the water front is thus heated by the combustion of gaseous fuel, thereby resulting in an unusually large volume of heated water with a comparatively small consumption of fuel. The primary result accomplished by thus heating both bodies of water when the gas burners are in use is that, by heating the water in the water front, local circulation (from the coil through the outlet branches into the water front) is prevented, thereby causing practically every heat unit to be utilized, an important object in the art to which the present invention relates. When the burners R, R' are lighted the openings m in the

door M are opened to admit a supply of oxygen for the consumption of gaseous fuel and the products of combustion may be permitted to pass out either by opening damper O or damper O'. If damper O is opened the products of combustion from the gas burners pass directly into the flue box D. On the other hand, if damper O' is opened the products of combustion pass over the top of the water front L into the firebox F before they are allowed to enter the flue box D. Control of the passage of such products in the latter manner may be preferable for the reason that the products of combustion passing over the top of the water front would tend to augment the heating effect on the water therein. When it is desired to heat the water by the consumption of solid fuel in the firebox, the openings in the door M are closed and also the long damper O'. In practising the latter method of heating, water enters the water front L through inlet pipe T and passes out of the water front through the outlet pipe T' without circulating in the coils at all, and thus no cooling effect is obtained, which would be the case if the water were allowed to circulate back into the gaseous fuel combustion chamber, before permitting it to pass to the boiler.

In the modification illustrated in Fig. 5, four single-barrel burners U are employed located one above the other and independently controlled, as hereinbefore set forth. The branch p of the pipe coupling P' is joined with the inlet end of a coil W consisting of a series of pipes located respectively above the superposed burners U and joined at their opposite ends by suitable elbows W'. The uppermost pipe of the coil is connected with the branch s of the coupling with the outlet pipe S. The same inlet and outlet connections are employed in this modification for the water front L as in the form shown in Figs. 1 to 4, inclusive. Another modification of the invention is illustrated in Fig. 6, wherein three superposed gas burners X are employed, all of which are located beneath coil Y, the latter consisting of two pipes joined by an elbow X'. One of the pipes of the coil is connected with the branch p' of the inlet coupling P' and the other pipe of the coil with the branch s of the outlet coupling S'. In this modification the same inlet and outlet connections are also employed for the water front.

What is claimed is:

1. In a range, the combination of a firebox for the consumption of solid fuel, a gaseous fuel chamber in proximity thereto, a water front interposed between and having its opposite sides exposed to the firebox and gaseous fuel chamber, water coils for the circulation of water located in the gaseous fuel chamber, a common inlet for

4
the coil and water front, a common outlet for the coil and water front, and gaseous fuel burners in the gaseous fuel chamber positioned immediately below the water coil 5 and immediately beside the water front so that the flame from said burners will impinge against said water front whereby when the gaseous fuel burners are used to heat water in the coil the water in the water 10 front will be heated to a degree to prevent local circulation between the coil and water front.

2. In a range, the combination of a firebox for the consumption of solid fuel, a 15 gaseous fuel chamber located in proximity thereto, a water front interposed between the firebox and gaseous fuel chamber, a coil for the circulation of water in the gaseous

fuel chamber including a pair of horizontally disposed pipes, a main inlet pipe having branches communicating with both the water front and the coil, a main outlet pipe having branches communicating with both the water front and coil, and gaseous fuel burners in the gaseous fuel chamber positioned immediately below the water coil and immediately beside the water front so that the flame from said burners will impinge against the water front whereby when the gaseous fuel burners are used to heat water 20 in the coil the water in the water front will be heated to a degree sufficiently high to prevent local circulation between the water coil and water front. 25 30

JAMES A. LANSING.
